UNITED STATES PATENT OFFICE.

LOUIS J. JARDOT, OF STILLWATER, OKLAHOMA.

BRICKLAYER'S GAUGE.

Application filed May 17, 1926, Serial No. 109,703. Renewed June 21, 1927.

My present invention has to do with means for facilitating the laying of bricks; and it contemplates the provision of a gauge calculated to enable inexperienced persons to accurately lay bricks and also calculated to be of material assistance to experienced brick layers in avoiding what are known as "hogs" in a wall.

Other objects and practical advantages of the invention will be fully understood from the following description and claims when the same are read in connection with the drawings, accompanying and forming part of this specification, in which:

15 Figure 1 is a view showing the preferred embodiment of my invention in use.

Figure 2 is an enlarged fragmentary elevation of a portion of the gauge hereinafter explicitly referred to.

20 Figure 3 is an enlarged horizontal section of the improved device.

Figure 4 is an edge elevation of the pointer and line supporting plate of the gauge.

Similar numerals of reference designate 25 corresponding parts in all of the views of the drawings.

Among other elements my novel gauge comprises a post or upright 1 of right angle form in cross-section. The said post 1 may 30 be five feet, more or less, in height, and it is provided with lateral bolts 2 and 3 relatively arranged as shown in Figures 1 and 3 and designed to carry spacing sleeves 4 and 5 and nuts 6 and also designed to serve for the 35 connection of threaded rods 7 and 8, the said threaded rods 7 and 8 being connected through the medium of turn buckles 9 with lower threaded rod sections 10, the latter being connected at their lower ends to arms 11 40 connected to the lower portion of the post 1 and extending at right angles to each other. The said arms 11 are adapted to form the base of the device and are also adapted to rest on an appropriate support so that the 45 turn buckles 9 and their connections may be used for convenient plumbing of the post 1.

In addition to the post 1 equipped as described, my novel gauge comprises a bracket 50 12 arranged to straddle the edges of the post 1 as designated by 13, and equipped with a threaded projection 14*. For the adjustable fixing of the bracket 12 to the post 1, I provide the said bracket 12 with a set screw 14 55 arranged to be engaged with the corner portion of the post 1, Figure 3.

At 15 is a plate having a vertical graduated scale 16 and also having an angularly disposed foot 17. The said plate is provided with a vertically disposed slot 18* 60 which receives the threaded projection 14* of the bracket 12 after the manner best shown in Figure 3.

Arranged against the face of the plate 15 is a plate 18 having an aperture which receives said threaded projection 14*, the plate 18 and the plate 15 being fixed to the brackets 12 through the medium of a wing nut 19 mounted on the threaded projection 14*. The said plate 18 is provided with a 65 pointer 20 for cooperation with the graduated scale 16, and said plate is also equipped at its lower end with a hook 21 designed to support in horizontal position a line 22, the said line 22 being preferably arranged with a pendent portion 23 which carries a weight member 24 at its lower end.

In the practical use of my invention, the upright post 1 is positioned at each corner of a building or wall in course of construction, and it will be understood in this connection that two of the posts 1 and the appurtenances thereof are used at one and the same time, the line 22 being stretched between the two gauges. Incident to the progress of the work and as each course of brick is laid the line 22 is raised adjacent to each corner as are also the plates 18, and consequently it will be easy for the brick layer to lay each course of brick absolutely level. 80 In this connection it will be appreciated that the plumbing of the upright post 1 averts the necessity of plumbing the corners, for at the corners the bricks are placed against the post 1 in substantially the relation shown in Figure 3.

It will further be appreciated from the foregoing that my novel gauge renders it unnecessary to squeeze joints at one end of a wall and raise joints at the other end in order to level a course of bricks, and that my improved device may be used to advantage by experienced masons as well as by novices.

I have explicitly described the preferred embodiment of my invention in order to impart a full, clear and exact understanding of the said embodiment. I do not desire, however, to be understood as limiting myself to the precise construction disclosed, my invention being defined by my appended claims within the scope of which modifica-

tions may be made without departure from my invention.

Having described my invention, what I claim and desire to secure by Letters Patent, is:—

1. In a gauge and in combination, a post of right angle form in cross section, arms connected to and extending at right angles from the lower end of the post and adapted to form a base, threaded bolts extending laterally from the post at an intermediate point in the height thereof and disposed at right angles to each other, spacing sleeves on the said threaded bolts, threaded rod sections secured on the said bolts of the post, threaded rod sections connected to the said base arms at points remote from the post, turn buckles interposed between and adjustably connecting said rod sections, a bracket straddling the post and adjustably fixed thereto and having a threaded projection, a vertically disposed plate having a graduated scale and also having a slot receiving said threaded projection on the bracket, a plate arranged in front of the first-named plate and apertured for the reception of said threaded projection and having a pointer for cooperation with said graduated scale

and also having means at its lower end for the support of a cord, and means on the threaded projection of the bracket for adjustably fixing the plates with respect to said bracket.

2. In a gauge and in combination, supporting means, a plate carried thereby and having a vertical graduated scale, and a second plate carried by the supporting means and having a pointer for cooperation with said graduated scale, and also having means for supporting a cord or line; one of the said plates being adjustable vertically with respect to the other.

3. In a gauge comprising a post, means for plumbing the same, a bracket adjustable vertically on the post and adjustably fixed thereto, and plates carried by the said bracket; one of the said plates being provided with a vertical scale and the other with a pointer for cooperation with said scale and also with means for supporting a line or cord, and one of the plates being adjustable vertically with respect to the other.

In testimony whereof I affix my signature.

LOUIS J. JARDOT.
